CIGARETTE HOLDER

Howard P. Thayer, Evanston, Ill.

Application April 27, 1934, Serial No. 722,688

5 Claims. (Cl. 206—38)

My invention relates to a holder wherein cigarettes may be accommodated and eventually snuffed. It may be used independently of any other article, or be associated with a box or comb 5 of matches in such a way as to be received substantially within the confines of such a container.

For its principal objects my invention aims to provide a holder which is economical to produce, which is small, light and easily accommodated 10 within the pocket or elsewhere, which lends itself readily to association with a container for matches and the like or other desired articles, and which will securely hold a lighted cigarette when placed therein and snuff the same if the burning 15 cigarette is allowed to continue. Such an article is advantageous in that it provides a safe repository for lighted cigarettes which are occasionally laid down for a few moments and sometimes forgotten with disastrous consequences. In addition, the 20 present holder may be used to accommodate ashes when no other suitable repository is conveniently at hand. These and other objects of my invention are attained by a holder for cigarettes or the like of which certain exemplifications are shown 25 in the accompanying drawing wherein—

Figure 1 is a perspective view of a conventional match box of the open tube and tray type with which is associated one form of the present holder;

Fig. 2 is a perspective view showing the tray slid 30 to expose the ends of contained matches and showing further the cigarette holder slid to operative position for receiving a lighted cigarette;

Fig. 3 is a perspective view of the cigarette holder per se;

Fig. 4 is a view of the blank from which the holder is formed;

Fig. 5 is a view in perspective of a modified form of the cigarette holder shown in association with a conventional match comb;

Fig. 6 is a perspective view of the comb opened up and the cigarette holder slid to operative position;

Fig. 7 is a detail in section on line 7 of Fig. 6; and

Fig. 8 is a view of the blank from which the holder of Figs. 5 to 7 is made.

In the present construction I have shown a holder which is made of a single piece of material, preferably sheet metal. It is also, in the forms shown, adapted for association with match containers of two different types, but, as will be readily apparent it may be used independently of any match container if this be desired.

Referring now to Figs. 1 to 4, I have illustrated

a conventional match box comprising an open-ended tube A wherein is slidably received a tray B containing a quantity of matches M. Fitted slidably between the tray and tube is the cigarette holder C which comprises a base 10 from which upstand a side wall 11 and a two-ply end wall 12. The holder may be produced from a blank as shown in Fig. 4 wherein I have indicated by dotted lines the folds which define in the section a the base 10, in the section b the side wall 11, and in the sections c and d the two-ply end wall 12. As shown, the section d is extended at one end as at 15 to join with an arm 16 whose opposite free end is provided with a laterally extending finger 17. In the completed article, the outer ply of the end wall 12 is bent over the upper edge of the inner ply to provide an edge piece 13. The extension 15 is then downturned to support the arm 16 adjacent the base 10. The finger 17 is upturned, and in response to spring action of the arm 16 is normally pressed close to the end wall 12.

A holder of this description is adapted to be fitted slidably between the tube A and tray B of the match box as shown in Figs. 1 and 2. 25 When so positioned, the holder may be slid outwardly from the match box independently of any movement of the tray. As shown in Fig. 1, the holder may be pushed all the way in so as to be accommodated within the confines of the tube. When pulled out to exposed position, as shown in Fig. 2, the end wall and spring arm together are adapted to serve as a holder for a cigarette. To serve in this capacity the free end of the arm is swung outwardly permitting 30 a cigarette to be rested upon the upper edge of the arm and by the upturned finger to be pressed against the end wall where it remains clamped in position. The lighted end of the cigarette is normally removed from the upstanding finger, but with continued burning the ignited portion of the cigarette will eventually reach a point opposite the finger. At such time the pressure imparted by the finger will act as a snuffer to extinguish the cigarette. Accordingly if a lighted cigarette be left in the holder for an indefinite time, it will be automatically extinguished in course of time without dropping out of the holder and onto some surface where damage might result.

A holder which is quite similar to the one just described, but modified somewhat for association with a match container of different type, is illustrated in Figs. 5 to 8 inclusive. Here I have shown a conventional match comb having 55

5 a back D with one end folded over to provide a clamping flap E and its other end likewise folded over to form a cover F adapted to be held in place releasably beneath the flap. Within the 10 container thus provided is a comb of matches M which may be secured in the usual manner as by a staple 20.

10 The cigarette holder formed for association with such a match comb may be made from a blank as suggested in Fig. 8. When set up, it provides a base plate 21 having an upturned flange 22 at one end, and at the opposite end a second flange 23 which continues upwardly to meet a second flange 24 which is downturned 15 from a top plate 25 extended laterally from a side wall 26 that upstands from one edge of the base plate. As shown, one corner of the base plate is cut out to clear the staple when inserted between the back D and the comb of 20 matches M. When so inserted the top plate 25 fits under the flap E and the flanges 24 and 25 which provide an end wall are also accommodated to the inside of the fold which connects the flap E with the back D of the match container. The 25 several parts of the holder just described are designated by corresponding reference characters on the blank shown in Fig. 8 wherein dotted lines indicate the lines of fold.

30 Connected to one end of the side wall 26 is a spring arm 30 having at its free end an upstanding finger 31 adapted normally, under spring tension, to lie adjacent the side wall. When sprung away from the wall a holder is provided for the reception of a cigarette in the manner already 35 explained. The holder may be pushed in so as to lie within the confines of the match container, as suggested in Fig. 5, or be pulled out to exposed position as shown in Fig. 6.

30 The extreme simplicity and effectiveness of the 40 present holder are in its favor. It may be used without danger to secure a lighted cigarette in place even when in physical association with a match container. In use, it firmly clamps a cigarette in place so that it may not accidentally 45 slide out or roll away to do damage which may be considerable.

I claim:

1. In combination with a match box which comprises a sliding tray within an open-ended tube, a cigarette holder formed of sheet metal bent to provide three connected walls of which two are adapted to fit slidably between the tray and tube whereby the third wall may be moved within the tube against the tray end or be pulled outwardly therefrom, a spring arm proximate to the third wall cooperating therewith to furnish a rest for a cigarette, and a finger extended laterally from the arm to lie transversely of the 10 rested cigarette adapted to snuff the lighted end thereof when consumed to a point opposite said finger. 5

2. In combination with a match retainer, a cigarette holder formed of sheet metal bent to provide connected walls adapted to slidably engage the retainer whereby to become connected therewith, the cigarette holder comprising a spring arm normally lying adjacent one of its 20 walls and formed with a laterally extending finger, the arm and finger cooperating with the adjacent wall to furnish a rest and snuffer for a cigarette which is positioned therebetween. 15

3. A cigarette holder in which is comprised a base together with an upstanding wall and a spring arm having an upturned finger normally positioned adjacent the wall, the arm when sprung away from the wall affording on its upper edge a rest for a cigarette which is pressed 30 against the wall by the finger. 25

4. A one-piece cigarette holder of sheet material bent to provide a base together with an upstanding wall folded down along its upper edge to form a spring arm one end of which is free 35 to swing away from the wall against the tension of the arm, there being an upstanding finger at the free end of the arm affording with the upper edge of the arm a rest for a cigarette. 40

5. A cigarette holder of sheet material bent to provide a base together with an upstanding wall from one edge of which is extended a spring arm normally lying close to the wall, and means on the arm cooperating with the wall for clamping a cigarette in place therebetween. 45

HOWARD P. THAYER.
